UNITED STATES PATENT OFFICE

HARRY J. COCKS, OF DES MOINES, IOWA, ASSIGNOR TO METAL PRODUCTS COMPANY,
OF DES MOINES, IOWA, A CORPORATION OF IOWA

HANGER FOR HATS, GARMENTS, AND THE LIKE

Application filed May 31, 1930. Serial No. 458,704.

The object of this invention is to provide an improved hanger device which is particularly designed for use by removably attaching it by a pin to upholstery, drapery, or other textile fabrics for the purpose of providing convenient means for supporting hats, garments or other objects.

A further object of the invention is to provide a convenient and simple hanger device which may be employed by pinning it to the upholstery of automobiles for supporting hats or other objects.

With these and other objects in view my invention consists in the construction, arrangement and combination of the various parts of my device, whereby the objects contemplated are attained, as hereinafter more fully set forth, pointed out in my claim, and illustrated in the accompanying drawings, in which:

Figure 1 is a perspective view of a portion of the interior of an automobile showing one of my improved hangers employed for supporting a hat.

Figure 2 is a front perspective view of the device.

Figure 3 is a rear perspective view of the device illustrating the pin supporting member.

Figure 4 is a vertical section through the device in position for use in supporting a garment, this section being taken on the line 4-4 of Figure 2.

Drivers or other occupants of automobiles frequently find it difficult to arrange a convenient means for carrying hats, coats and the like, so that they will be out of the way of the occupants of the seats and at the same time be secured against danger of being blown out of the vehicle.

My present invention relates to a simple and inexpensive device which may be supported in any suitable location by pinning it to the upholstery of the vehicle, the device being arranged for securely gripping and holding a hat, coat or other garment or similar object so that the object so suspended will be entirely out of the way of the occupants of the seats, and yet will be easily accessible when desired for use.

The device is mainly formed from sheet metal and includes a back plate 10 formed with a pair of forwardly projecting ears 12 on its side margins intermediate of its ends. The ears 12 are apertured in alignment to receive a pintle pin 14.

A clamping member 16 is formed of a strip of metal of approximately the same width as the back plate 10 and said clamping member is formed on its side margins and intermediate of its ends with a pair of apertured ears 18. The ears 18 are received between the ears 12 of the back plate and pivotally engage the pintle pin 14.

The main portion of the clamping member 16 is spaced from and is substantially parallel with the back plate 10. Toward its lower end the clamping member 16 is offset toward the back plate 10, thus providing a substantially horizontal supporting portion 20 and a vertical terminal flange 22 which normally contacts with the lower end of the back plate.

Mounted on the pintle pin 14 between the ears 18 of the clamping member is a coil spring 24 which has its end portions extended and engaging respectively the upper ends of the back plate 10 and clamping member 16 in such manner as to urge said upper portions apart and to cause the terminal flange 22 of the clamping member to be held forcibly toward the lower end of the back plate.

The upper end of the clamping member 16, above the pivot point, may be bent outwardly somewhat and shaped to form a finger-engaging portion or handle 26.

An attenuated suspending or pinning member 28 is arranged on the rear side of the back plate 10 and has its upper end attached thereto in a suitable manner as by extending it through openings 30 in the back plate and bending it to embrace a portion between said openings as clearly shown in Figure 4.

The suspending member 28 or pin preferably is rather long and is adapted to be inserted into or through textile fabric such as 32 for supporting the hanger in the desired position. The fabric 32 may be a portion of the upholstery of an automobile such as is shown in part in Figure 1 and designated generally by the numeral 34.

When the hanger is mounted as above described it may be employed for suspending a hat such as 36 in the manner illustrated, in Figure 1. It will be understood that the lower or terminal flange 22 of the clamping member may be moved away from the back plate 10 by manual pressure applied to the finger portion 26, against the influence of the spring 24, for the purpose of inserting or removing an object from the hanger. The spring 24 preferably is relatively strong so that a firm and secure gripping action may be had upon the brim of a hat or upon any suitable portion of an object to be suspended.

15 I prefer to make the offset portion 20 of the clamping member as shown particularly in Figures 3 and 4, so that it is inclined upwardly slightly from the main portion of the clamping member and toward the back plate.

It will be noted that the offset portion 20 of the clamping member is capable of providing positive supporting means for an object as distinguished from the merely frictional support which is provided by the spring pressed relation of the terminal flange 22 to the back plate.

20 This method of suspending an object is illustrated particularly in Figure 4 in which a garment such as a coat 38 is shown as having a portion extended between the substantially parallel parts of the back plate and clamping member and overlying the offset portion 20.

25 In this way the object may be more securely suspended from the hanger and it will be noted that this relation is enhanced by the upwardly inclined arrangement of the portion 20. This upward inclination need not be great, but preferably is sufficient so that when the lower part of the clamping member is swung outwardly through an arc, the portion 20 will still be in such position as to provide the desired positive support for 30 an object.

35 It is to be understood that various alterations and modifications may be employed within the scope of the appended claim and also that the device may conveniently be used for different specific purposes and in other locations than those herein illustrated and described.

40 I claim as my invention:

45 A hanger for hats, garments and the like, comprising a back plate, a clamping member spaced from and pivotally connected between its ends to said back plate, a spring for urging the lower part of said clamping member toward the back plate, the lower part of said clamping member being offset 50 toward the back plate to provide a substantially horizontal portion constituting a positive object-supporting member, said offset portion being inclined upwardly somewhat 55 toward the back plate, and a pin carried by

said back plate for engaging upholstery or the like for suspending the hanger and an object carried thereby.

Des Moines, Iowa, April 22, 1930.
